ELECTROPLATING APPARATUS

Application filed November 16, 1929. Serial No. 407,604.

This invention relates to new and useful improvements in electroplating apparatus. Heretofore, electroplating apparatus of the type to which this invention appertains used 5 a revoluble barrel or tank wherein the negative connector or cathode was attached to the inside of the barrel and was placed in the electric circuit through connections which extended outwardly from the barrel to a ring 10 arranged on the underside thereof and by means of a stationary brush engaging said ring.

This arrangement has been unsatisfactory for several reasons, one of which was the 15 tendency of the plating deposit to "tree out" and spread from the cathode element to adjacent surfaces. Thus a frequent removal and cleaning of the cathode element was necessary to remove the deposit therefrom. If 20 this frequent cleaning did not take place, the deposit would continue to spread until the barrel would be electroplated more than the load contained therein. Such periodical cleaning requires a considerable amount of 25 time and labor and renders the apparatus disabled for a considerable length of time. Furthermore, this construction calls for special work on the barrel in order to fit the rings in 30 position and establish electric connections 35 therebetween.

The present invention has for its objects the provision of an electroplating apparatus 40 wherein both elements, namely, cathode and anode, are mounted independently of the barrel and are insertable thereinto through the open upper end thereof, the cathode element being insulated from and spaced below the anode element and arranged so that it rests 45 freely against the bottom of the barrel and is maintained in close and efficient electric contact with the load or objects placed in the 50 barrel.

Further objects of the invention are to detachably mount both of said elements so that 55 they can be easily installed or removed for cleaning purposes and to make said elements of inexpensive construction so that new ones can be readily substituted for the old elements.

50 Other objects of the invention are to pro-

vide an improved anode element adapted to be detachably supported in position and having its underside provided with a series of concentrically arranged ribs or convolutions in order to increase the surface thereof and insure efficient contact with the electrolyte. 55

Still other objects of the invention are to provide an improved mounting for said cathode and anode elements whereby they can be adjusted to various heights with regard to 60 the barrel and can be readily moved to remote positions with respect to said barrel.

Still further objects of the invention are to provide an improved mounting for the cathode element whereby the latter can be 65 easily detached from position and a new one substituted in place thereof and whereby said cathode is flexibly supported so as to accommodate itself to the bottom of the barrel and the load contained therein. 70

Additional objects of the invention are generally to improve upon the construction and operation of the electroplating apparatus of the type using open-topped revoluble barrel and to reduce the installation and 75 maintenance costs of such apparatus.

With these and other objects in view, our invention consists in certain novel features of construction and arrangement of parts, hereinafter more fully described and claimed, 80 and illustrated in the accompanying drawings, in which—

Figure 1 is a side elevational view of our 85 improved apparatus showing the barrel partly in cross section.

Figure 2 is a rear elevational view thereof.

Figure 3 is a cross section taken on line 3—3 of Figure 1.

Figure 4 is an enlarged vertical cross section through the anode and cathode elements 90 and the supporting parts thereof.

Figure 5 is an enlarged vertical cross section through the upper ends of the supports utilized for said elements.

Figure 6 is a horizontal cross section taken 95 on line 6—6 of Figure 5.

Figure 7 is an enlarged elevational view of the anode element, looking against the underside thereof.

Briefly stated, the apparatus to which our 100

invention is especially applicable utilizes a revoluble barrel disposed with its axis inclined from vertical and having the upper end open. This barrel is filled with suitable 5 electrolyte and is actuated so as to cause tumbling or agitation of the load contained therein, thereby insuring efficient electroplating of said load or objects. The anode and cathode elements are submerged in the electrolyte 10 and are insulated and spaced from each other. As disclosed in the present invention, these elements are stationarily supported and are so arranged that they can be easily withdrawn from the barrel and readily detached 15 from their supports.

Referring by numerals to the accompanying drawings, 10 indicates a base provided on each side with a horizontally disposed bearing 11 in which are journaled shafts 12. 20 The inner ends of said shafts project from said bearings and have mounted thereon horizontally disposed bearings 14 of a casting 15. Bearings 14 are formed integral with casting 15 and are spaced from each other so as to 25 form a central clearance within casting 15. A pair of bearings 16 is formed integral with casting 15 substantially at right angles to bearings 14 and are adapted to have journaled therein trunnion shaft 17 of a plating 30 barrel 18. This shaft 17 is secured in position on said barrel by means of a series of radial arms 17^a which extend from the hub portion 17^b and are secured to the underside or bottom 18^a of barrel 18. 35 Bearings 16 are spaced from each other a suitable distance and fixed to shaft 17 is a large gear 19 which is engaged by a beveled pinion 20. The latter is fixed to the inwardly projecting end of one of the shafts 12 and the 40 outer end of said shaft has fixed thereon a large pulley 21 over which operates a belt 22 driven by a motor 23. Thus the actuation of the motor rotates pinion 20 and through it large beveled gear 19 which actuates shaft 45 17 and barrel 18 carried by said shaft.

Barrel 18 and casting 15 are tiltable about the axis of shafts 12 whereby the barrel 18 can be maintained in operative position as shown in full lines in Figure 1 or can be 50 tilted downwardly to empty the electrolyte and the load as shown in dotted lines in said figure. In order to hold said barrel in operative position and to provide means for tilting said barrel, a handle 24 is provided. 55 This handle is arranged to one side of the apparatus and is fixed at its lower end to a rock shaft 25 which has bearing in the base 10 and extends between the sides thereof.

A pulley 26 is fixed on said rock shaft, preferably immediately below the axis of barrel 18, and operating over said pulley is a chain 27, one end of which is fixed to said pulley and the other end of which is fixed to an extension 28 which projects rearwardly from 65 casting 15. Thus by operating handle 24

in the proper direction, shaft 25 is rocked to either release chain 27 and permit downward movement of the barrel, or to wind the chain on its pulley and raise said barrel in position.

Handle 24 is locked in adjusted position by means of a pawl 29 engaging ratchet teeth on segment 30. Pawl 29 is operable in the usual manner by a latch 31. The extension 28 has suspended therefrom a counter weight 32 which counterbalances the barrel 18 and facilitates the adjustment thereof on the axis of shafts 12.

Bearings 14 have formed integral therewith transversely and rearwardly disposed bearings 14^a. These bearings receive the 80 lower ends of a pair of lower members 34 of a frame 35. Where said ends enter bearings 14^a they are insulated therefrom by suitable insulating members 36. The opposite ends of members 34 are connected by suitable coupling members 37 to the lower ends of a pair of upwardly and forwardly inclined members 38. These members extend upwardly a suitable distance above barrel 18 and are connected together by suitable couplings 39 and a horizontally and transversely disposed member 40.

This member 40 is preferably tubular in cross section and has loosely mounted thereon a bearing or socket member 41. This socket member is free to move in an arc of about ninety degrees, the extent of rocking movement thereof being limited by a pin 42 which is seated in member 40 to one side of member 41 and engages a notch formed in the corresponding end of said member. A collar 44 is preferably secured to member 40 on the opposite side of member 41 so as to prevent longitudinal movement of member 41 on the horizontal support 40.

A tubular extension of socket member 45 is formed integral with member 41 and has its bore disposed at right angles to the bore of member 41. A tubular sleeve 46 extends slidably through socket 45 and has its upper end provided with an adjustable clamp 47 which limits the downward movement of member 46 and supports the latter in suspended position. The lower end of tubular member 46 is threaded and has screw-seated thereon an anode element 48. This anode element is of circular shape and is provided on its underside with a series of concentrically arranged ribs or convolutions 49 which increase the effective surface of said anode. This anode is provided with a central aperture for receiving the tubular member 46 and the supporting means 50 carrying cathode 51.

The cathode or negative element 51 is of spherical shape and is secured to the lower end of a cable or flexible connection member 52. This cable has the usual insulation 53 and in addition is provided with an outer insulation rubber covering 54. The lower end of said cable extends a suitable distance

below anode 48 and permits cathode 51 to be moved about in all directions so as to insure an efficient electrical contact between said cathode and the load contained in the barrel. 5 Where the cable enters the lower face of anode 46 a sleeve of fiber or rubber, such as 55, is arranged in the central opening of said anode and projects a suitable distance therebelow so as to prevent said cable and its insulation covering from coming in direct contact with said anode. Said cable fits snugly within sleeve 46 and can be readily removed therefrom. 10

The upper ends of insulating material 53 and 54 terminate substantially flush with the upper end of metal tube 46. The upper end of this tube is threaded and receives a cap 56, the upper end of which is provided with a central opening. A washer 57 is placed 20 over the upper ends of tube 46 and insulating covers 53 and 54 and is held thereagainst by said cap 56. This washer is provided with an upwardly presented reduced extension 57^a which extends through the opening formed in 25 said cap 56. The upper end of the cable extends upwardly a suitable distance above cap 56 and is insulated from the latter by means of said washer 57 and extension 57^a. A terminal block or connector 58 is secured to the 30 extreme upper end of cable 52 and seated in said connector is one end of an electrical connection 59 which leads to the negative pole of a generator (not shown).

An insulation washer 60 is inserted between block 58 and cap 56 so as to preserve the insulated relation between cable 52 and tube 46. 35

Adjusting collar 47 is clamped in fixed position on tube 46 by means of a handle 61. 40 Collar 47 is split and is provided with laterally projecting lugs 47^a in one of which is screw-seated one end of a screw 62. The opposite end projects outwardly from the other lug and has fixed thereon said handle 45 61. Thus by turning the handle in the proper direction, said lugs are drawn together to clamp the collar on said tubular member 46.

This collar forms a terminal connector for the positive lead or connection 63 of the electric circuit, there being a forward extension 64 formed on said collar which extension is provided with a bore for receiving the end of said connection. The electrical connection between the lead 63 and anode 48 is completed by tube 46 which is formed of metal. 50 Thus the current passes from connection 63 and lug 64 to collar 47 and then through tube 46 to anode 48. From the anode the electric current passes through the electrolyte and acts on the load or objects placed in the barrel. 55 The circuit is completed by the cathode 51 which is in intermittent contact with the load and is connected through cable 52 and terminal block 58 to the other lead 59.

60 As shown in the drawings, the socket 45 is formed of metal and is in electrical contact with tubular member 46. Therefore frame 35 is insulated from the rest of the structure by means of insulation members 36. However, socket 45 could be provided 70 with an insulating sleeve whereby tubular member 46 would not be in electrical contact with the socket and would therefore be insulated from the supporting structure and in which case the insulating members 36 could 75 be dispensed with.

When it is desired to load or unload the barrel, the cathode and anode elements are moved into the position shown in dotted lines in Figure 1. In this position the tubular member 46 is moved longitudinally through the socket member 45 and said socket member is tilted from vertical position into horizontal position on support member 40 so that said elements and parts associated therewith are completely out of the way of the operator. 80

To remove the cathode element from the assembly, the terminal block 58 is detached from the upper end of cable 52, whereupon 90 said cable and its insulation covering can be withdrawn from tubular member 46. To remove the anode element 48, the same is unscrewed from the lower end of tubular member 46. This member can be removed by 95 detaching cap 56 from the upper threaded end of the tube. The adjusting collar 47 is movable on tubular member 46 so as to control the downward movement thereof and regulate the positioning of the elements and particularly the anode element. 100

In order to facilitate the removal of cable 52 and its insulation covering from tubular member 46, block 58 is preferably attached to cable 52 by means of a set screw 65. 105

The tubular member 46 is provided throughout its entire length with insulating lining members 46^a which insulate the supporting means 50 from said tube 46 so that under no circumstances does said supporting means 50 (which includes cable 52, insulation covering 53, and gum rubber covering 54) come in contact with said tube 46 or anode 48. 110

Thus an efficient insulation is maintained at all times between said anode and cathode elements and their connections. The sleeve 55 in addition to its insulation feature also serves to protect the projecting portion of means 50 against injury at its point of emergence from the anode 48. 115

The particular arrangement of anode and cathode elements permits easy displacement thereof with respect to the barrel and enables quick replacement of the elements. The cathode 51 is flexibly mounted so that it will 120 give and adjust itself to the load contained in the barrel, thereby insuring efficient electrical contact with the load at all times. 125

As both the anode and the cathode elements are mounted independently of the barrel no 130

additional work on the barrel is required. All danger of leakage of the electrolyte through imperfect connections is eliminated.

While we have disclosed herein the preferred embodiment of our invention, it is obvious that various changes in the construction and arrangement of parts of our improved electroplating apparatus could be made and substituted for those herein described and shown, without departing from the spirit of our invention.

We claim:

1. An electroplating apparatus comprising in combination a revolute open-topped electrolyte container, a stationary frame extending above said container, a tubular support mounted on said frame and extending into said container, said support being adjustable in vertical plane, a centrally perforated anode fixed to the lower end of said support, a flexible connecting member extending through said support, the lower end of said connection extending through said anode, into said container, a cathode fixed to the lower end of said flexible connection member whereby said cathode has a restricted free movement within said container below said anode, a terminal anode connector fixed to the upper end of said tubular member, a terminal cathode connector fixed to the upper end of said flexible connection and electrical connections for connecting said terminal connectors to the respective poles of a generator.

35 2. An electroplating apparatus comprising an open-topped container mounted for rotation on an inclined axis, a stationary frame extending above said container, a socket member mounted on said frame and movable from vertically disposed operative position into an inoperative horizontal position, a tubular member slidably mounted in said socket and extending into said container, an anode fixed to the lower end of said tubular member, an adjusting collar fixed to said tubular member near the upper end thereof and adjustable thereon to regulate the vertical movement of said tubular member, a flexible cable extending through said tubular support and insulated therefrom, a cathode fixed to the lower end of said cable and spaced a suitable distance below said anode, means for securing the upper end of said cable in insulated relation to said support, and electrical connections for connecting said anode and cathode to the respective poles of a generator.

60 3. An electroplating apparatus comprising an open-topped container mounted for rotation on an inclined axis, a stationary frame extending above said container, a socket member mounted on said frame and movable from vertically disposed operative position into an inoperative horizontal position, a tubular member slidably mounted in

said socket and extending into said container, an anode fixed to the lower end of said tubular member, an adjusting collar fixed to said tubular member near the upper end thereof and adjustable thereon to regulate the vertical movement of said tubular member, a flexible cable extending through said tubular support and insulated therefrom, a cathode fixed to the lower end of said cable and spaced a suitable distance below said anode, means for securing the upper end of said cable in insulated relation to said support, an electrical connection secured to said adjusting collar for connecting the positive pole of a generator to said anode, and an electrical connection secured to the extremity of the upper end of said cable for connecting said cathode to the negative pole of a generator.

4. In an electroplating apparatus, the combination of an open-topped container mounted for rotation on an inclined axis, a stationary frame extending above said container, a vertically disposed socket mounted on said frame above said container in a vertical plane with the top thereof, said socket being movable on a horizontal axis into a horizontal position, a tubular member slidably mounted in said socket and extending when in vertical position into said container, a centrally apertured anode fixed to the lower end of said tubular member, a flexible cable extending through said tubular member and insulated therefrom and from the electrolyte contained in said container, a cathode fixed to the lower end of said cable and spaced below said anode, and electrical connections connected respectively to the upper ends of said tubular member and of said cable.

5. In an electroplating apparatus, the combination with an open-topped container, of a stationary frame extending thereabove, a socket member carried by said support above said container and movable into vertical and horizontal positions, a metallic tubular member slidably mounted in said socket member and extending into said container, a centrally apertured anode fixed to the lower end of said tubular member, a collar fixed to the upper end of said tubular member and bearing against the upper end of said socket to limit the downward movement of said tubular member and said anode, a flexible insulated cable fixed in said tubular member and extending below said anode, said cable being insulated throughout its entire length from said tubular member and from the electrolyte contained in said container, a cathode fixed to the lower end of said cable and loosely disposed in the bottom of said container, an electrical connection connected to said collar for connecting said anode to one pole of a generator, and an electrical connection connected to the upper end of said cable for connecting said cathode to the other pole of a generator.

6. In an electroplating apparatus of the

class described, the combination of a support including a socket member, a metallic tubular member slidably mounted in said socket and extending downwardly therefrom, a central
5 apertured anode fixed to the lower end of said tubular member, a collar fixed to the upper end of said tubular member and bearing against the upper end of said socket to limit the downward movement of said tubular
10 member, means for adjustably securing said collar on said tubular member so as to regulate the downward movement of the latter and of said anode, a flexible cable extending through said tubular member and projecting
15 therefrom below said anode, said cable being insulated throughout its entire length, a cathode fixed to the lower end of said cable, an electrical connection fixed to the upper end of said cable and connecting said cable and said
20 cathode to one pole of a generator, means for insulating said electrical connection from the upper end of said tubular member, and an electrical connection attached to said collar for connecting said tubular member and said
25 anode to the other pole of a generator.

In testimony whereof we hereunto affix our signatures this 9th day of November, 1929.
